(57) **CLAIM**

The ornamental design for a dispenser for dispensing fragrances, as shown and described.

DESCRIPTION

FIG. 1 is a perspective view of a dispenser for dispensing fragrances showing our new design;

FIG. 2 is a front elevational view thereof;

FIG. 3 is a back elevational view thereof;

FIG. 4 left side elevational view thereof;

FIG. 5 right side elevational view thereof;

FIG. 6 is a top plan view thereof; and,

FIG. 7 is a bottom plan view thereof.

The broken lines shown in the drawing views are included for the purpose of showing environmental structure that forms no part of the claimed design.
